UNITED STATES PATENT OFFICE.

SAMUEL CLAY, OF GARWOOD, TEXAS.

AUTOMATIC WRENCH.

1,049,995.

Specification of Letters Patent. Patented Jan. 7, 1913.

Application filed April 1, 1912. Serial No. 687,707.

To all whom it may concern:

Be it known that I, SAMUEL CLAY, a citizen of the United States, residing at Garwood, in the county of Colorado, State of Texas, have invented certain new and useful Improvements in Automatic Wrenches; and I do hereby declare the following to be a full, clear, and exact description of the invention, such as will enable others skilled in the art to which it appertains to make and use the same.

This invention relates to new and useful improvements in automatic wrenches.

An object of this invention is the provision of a wrench of such construction that the movable jaw can be locked in its adjusted positions, the said jaw being of such construction that upon its release it will be automatically moved to its extended position away from the stationary jaw.

A further object of this invention is to improve and simplify devices of this character, rendering them comparatively simple and inexpensive to manufacture, reliable and efficient in use and readily operated.

With the above and other objects in view, this invention resides in the novel features of construction, formations, combinations and arrangements of parts to be herein-
after more fully described, claimed and illustrated in the accompanying drawing, in which:

Figure 1 is a side elevation of my invention. Fig. 2 is a longitudinal sectional view thereof, with the sliding jaw at its limit of outward movement on the stock and the pawl in locking engagement with the rack bar. Fig. 3 is a transverse sectional view taken on the line 3—3 of Fig. 1, and Fig. 4 is a similar view taken on the line 4—4 of Fig. 1. Fig. 5 is a longitudinal sectional view showing the sliding jaw at its limit of inward movement on the stock with the pawl released from the rack bar.

Referring to the accompanying drawing by similar characters of reference throughout the several views, the numeral 5 designates generally my improved wrench which consists of the customary stock 6 which is formed at one end with a stationary head 7 and at intervals throughout its length with perforations 8 for the reception of bolts 9 or other suitable fastening devices by means of which the handle 10 is secured thereon and held against displacement.

The handle 10 is substantially U-shaped in

cross section consisting of the customary legs 11 which engage the opposite sides of the stock 6 and receive the fastening devices 9, the said legs 11 being connected by an arch portion 12 which extends in spaced relation from the adjacent edge of the stock 6 to produce a passage 13 in which is slidably located an operating rack bar 14 to one end of which is secured in any manner the movable jaw 15 for movement to and from the said stationary jaw 7 for coöperation therewith.

The inner edge of the rack bar 14 is formed with a plurality of teeth 16 for engagement with the sharpened end 17 of a pawl 18 pivoted intermediate its ends as at 19 to a finger 20 which projects into the notch or pocket 21 formed in the bar 6 and in which the said pawl 1 is located.

A spring pressed pin 22 engages the operating end of the pawl 18 and serves to normally force the terminal 17 thereof into engagement with the teeth 16, while bearing against the opposite ends of the said pawl as at 23 is an operating pin 24 which projects through an opening formed in the stock 6. It is provided with a head 25 by means of which the said pin can be forced inward and the terminal 17 disengaged from the teeth 16.

A retractile spring 26 is attached to the end of the handle 10 and to the adjacent end of the rack bar 14 and serves to automatically slide the jaw 15 to its extended position upon the release of the rack bar 14.

The jaw 15 is limited in such movement by its contact with the adjacent end of the handle 10 and the said jaw can be readily moved to its retracted position against the tension of the spring 26 by simply releasing the pawl 18 and sliding the said jaw 15 in the direction of the jaw 7 to the desired position, in which it will be retained upon the release of the pawl 18.

It should be understood in this connection that various minor changes in the details of construction can be resorted to within the scope of the appended claims without departing from or sacrificing any of the advantages of the invention.

From the foregoing disclosure taken in connection with the accompanying drawing, it will be manifest that a wrench such as described which will fulfil all of the necessary requirements of such a device is provided.

Having thus fully described this invention

what I claim as new and desire to protect by Letters Patent, is:

1. In a wrench, the combination of a stock having a stationary jaw, a tubular handle connected to the stock, a jaw sliding on the stock, a rack bar connected at one end to the sliding jaw and extending into the handle, retracting means connected to the rack bar and normally tending to draw the sliding jaw away from the stationary jaw, a pawl located in a recess in the stock and pivoted centrally, a spring tensioned reciprocating member bearing against the outer edge of the pawl and normally holding the same in locking engagement with the rack bar, and a depressible pin extending through the back of the stock and bearing against the opposite end of the pawl for depressing such end to release the pawl from locking engagement with the rack bar.
2. The combination of a stock carrying a

stationary jaw, a handle carried by the stock and provided with a longitudinal passage, a jaw sliding on the stock, a rod connected at its outer end to the sliding jaw and movable within the passage, said jaw having rack teeth thereon, a finger formed on the stock and extending into a recess in the stock, a locking pawl pivoted centrally to the finger, a spring tensioned pin normally holding one end of the pawl in locking engagement with the rack, and depressible means adapted to bear against the opposite end of the pawl and designed when depressed to release the pawl from locking engagement with the rack.

In testimony whereof, I affix my signature, in presence of two witnesses.

SAMUEL CLAY.
